UNITED STATES PATENT OFFICE.

GEORGE EDGAR HAZARD, OF ROCHESTER, NEW YORK, ASSIGNOR TO KELLOGG MANUFACTURING CO., OF ROCHESTER, NEW YORK.

PRESSURE-CONTROL DEVICE.

Application filed December 8, 1926. Serial No. 153,296.

This invention relates to improvements in pressure control devices and is particularly intended for controlling the pressure produced by a pump or similar mechanism used 5 for producing pressure for washing automobiles or the like.

In devices of the above character the water is supplied by a pump or other device to what is referred to in the art as a car washer 10 gun, which gun has its nozzle or outlet at times closed and at other times partially closed and it is the primary object of this improvement to cause a circulation of the water through the pump when the gun is 15 shut off or partially shut off. In carrying out this improvement I have provided a device that is located between the pump and the said gun, whereby when the said gun is completely closed or partially closed, the 20 circulation of the water that otherwise would flow through the gun, is returned through the pump to cause a continuous circulation of the water irrespective of the operation of the 25 said gun.

It will be understood that in the operation of a device of the character mentioned, the said pump will be continuously operating whether the gun be in use or out of use.

In washing cars the user of the gun cuts it 30 off completely or partly from time to time, and when its use is stopped, the gun is cut off and by this improved device the water continues to automatically circulate through this device and through the said pump, and 35 the gun is always ready for use.

In the accompanying drawings:

Figure 1 is a vertical central sectional view on the line 1—1 of Figure 2.

Figure 2 is a top plan view of Figure 1.

The drawings do not disclose a car washer 40 gun since any form may be used that has means for controlling the flow of water through it. Therefore any ordinary nozzle that is adapted to be closed, may be used and it is deemed unnecessary to illustrate the 45 said device.

The same is likewise true in connection 50 with the water pump for supplying the water under pressure to the nozzle of the gun. Any well known type of pump may be used without departing from the spirit of the invention, and it is therefore deemed unnecessary to illustrate the said pump.

Referring to the accompanying drawings 55 in which the body of the device for effecting

the above function, is designated by numeral 1, this body portion has an inlet 2. This inlet is suitably connected substantially directly with the pump, or a hose or like connection that has its opposite end connected with the pump (not shown). This inlet 2 has its inner end communicating with a suitable chamber 3 formed in the body portion 1. A check valve 4 is located at the bottom of the body 1 and it controls an opening 5 that communicates with a suitable chamber 6 that has a return outlet 7 that communicates with the said pump (not shown). The housing also is provided with a space 8 and above this space is located a flexible diaphragm 9 that 60 covers the entire top of the body 1. Located on top of this diaphragm is a housing 10, the said housing having an opening 11 that communicates with an outlet 12 formed in the said diaphragm. The said opening 11 is controlled by a suitable check valve 13 that is seated on a member 14 that is screwed into said opening 11. This opening 11 communicates with a chamber 15 that is located 65 over the diaphragm 9 and this chamber has 70 an outlet passageway or opening 16 that leads to the car washer gun or guns as the case may be. This opening 16 may be in the wall 16'. Attached to the top of this chamber 15, is an ordinary pressure dome 17 through a passageway 17' that is connected with the said chamber 15 as shown. The object of this chamber 17 (which is partially 75 shown) is to form an air pressure in the upper portion of the chamber to cause a uniform pressure at the gun or guns. In other words provides for the ordinary air pressure dome that operates as usual in connection with pumps.

A plunger 18 is located under the diaphragm and this plunger is provided with a downwardly extending stem 19 that is in enlargement with the check valve 4 for a purpose to be presently explained.

A spring gun barrel 21 is screwed into an opening 22 formed in the lower portion of the body 1, and the lower end of this gun is closed by a suitable cap 22. Located in this barrel is a spring 23 that carries at its upper end a cap 24 that is in engagement with the check valve 4 while its lower end 25 is in engagement with an adjustable part 26 that screws within the lower portion of the barrel for the purpose of regulating the upward pressure exerted by the said coil spring 100 105 110

23. For the purpose of connecting the inlet 2 directly with a pump structure, a lateral flange 1' is provided and it has bolt openings 3' for dirt.
- 5 Having described the construction and its several parts and members, its operation will now be explained.
- 10 The pump being in operation, forces water through the hose connection 2' to the chamber 3 from which the water is forced through the openings 11 and 12, thus lifting the check valve 13, hence into the chamber 15 through the opening 16 to the hose 25 and to the car washer guns. Assuming the guns to be in
- 15 operation, the water flows in the manner just described. If one or more of the guns are closed off or the flow of water through one or more of these is cut down, then the pressure in the chambers 3 and 15 is increased.
- 20 Consequently the increased pressure closes the valve 13 and forces the diaphragm 9 downward, carrying with it the plunger 18 and the stem 19, displacing the check valve 4 when part or all of the water will flow past
- 25 the check valve 4 into the chamber 6 through the return passageway 7 to the said pump, thus causing the water to circulate through the passageway to chambers 3 and 6 to the pump, etc., making it a continuous circulation through the pump instead of through the gun or guns, while at the same time the pump continues in operation.

The above described improvement may be

varied somewhat in detail without departing from the spirit and scope of my invention so long as it will come within a fair interpretation of the appended claim. 35

Having thus described my invention, what is claimed and desired to be secured by Letters Patent is:

40 A pressure controlling device comprising a housing having upper and lower chambers substantially in a vertical line and a third chamber located to one side of said chambers and below the upper chamber, said third chamber having its lower portion in communication with the lower chamber and its upper portion in communication with the upper chamber, a downwardly closing valve controlling communication between the upper chamber and the third chamber and an upwardly spring actuated valve controlling the communication between the lower chamber and said third chamber, said upper and lower chambers having outlets, a diaphragm 45 in the upper chamber, a downwardly projecting member actuated by the diaphragm for unseating the valve controlling the communication between the lower chamber and the third chamber, said third chamber having 50 an inlet, whereby said device operates in the manner specified. 55

55 In testimony whereof I hereunto affix my signature.

GEORGE EDGAR HAZARD.
